SHOULDER PAD AND METHOD OF FABRICATING THE SAME

Simon Kagan and Irving Rothenberg,
New York, N. Y.

Application November 2, 1944, Serial No. 561,515

3 Claims. (Cl. 2—268)

1

The present invention relates to a shoulder padding used in the manufacture of garments, such as women's dresses, which shoulder padding is in the nature of a hidden epaulet to build up and impart shape to the shoulder of the wearer of the garment, and the method of manufacturing it.

Heretofore, shoulder pads of the kind here concerned with were made from two superposed similarly shaped separate plies of material, each somewhat in the form of a half ellipse, and which are sewed together so that the edges of the plies are bound in a ribbon to form a trimmed edge. This ribbon trim is folded over upon itself with the edges of the plies arranged between the folds of the ribbon, which are all then sewed together.

In manufacturing such prior art pads, a continuous ribbon is used to sew the straight edges at the back of the pad and another continuous ribbon is used to sew the curved edges at the front of the pad. As a result there is formed a continuous string or strip of pads each separated by a portion of the sewed together ribbons, which must then be cut at these intermediate spaces to form the individual separate pads.

The trimmed or bound edges of these prior art pads often came apart, particularly when they were separated from each other in the formed strip or string and when the garment to which they were attached was washed or cleaned. Further, these trim edges were apt to be comparatively rough and were not uniformly sewed because of the shifting of the ribbon. Since the two plies had to be matched, it was also difficult for this reason to provide pads that were uniform in size and shape, this unevenness adding to the difficulties of manufacture.

The present invention contemplates the provision of such a pad made from but a single ply of material, approximately elliptical in plan view and folded over upon itself to form a pad that is somewhat half elliptical in plan view, thus eliminating a cutting and the matching operation.

The present invention further contemplates the provision of such pad in which the ribbons for trimming or binding the edges are eliminated, in this way further reducing the cost of manufacture. We accomplish this by using a blank formed from a single ply of material folded over upon itself to form a straight untrimmed edge at the back of the pad, which cannot separate and sewing the curved edges at the front of the pad with a relatively close overlocking stitch, the threads of which constitute the trimmed edge of the pad thus further eliminating material and reducing cost.

Our invention therefore dispenses with one operation of stitching and results in the manufacture of a strip or string of pads which are connected together at the ends thereof by the overlocking stitching itself and not by the ribbons.

2

which trim the edges of prior art pads. As a result when the pads are separated by cutting the overlocked stitching of thread, the trimmed front edges will not separate since the ends are formed from the stitching itself nor will they, by reason thereof, separate when the garment, to which they are attached, is washed.

Further, the trimmed edges provided by the construction and method of manufacture contemplated by our invention will be uniform and present a smooth and even finish or binding that will not cause any discomfort as was at times wont to happen with the pads of the prior art.

These, other and further objects and advantages of the present invention will be clear from the description which follows and from the drawings appended thereto in which

Fig. 1 is a plan view of a blank of material that is used to form a pad pursuant to our invention;

Fig. 2 is a similar plan view, showing the blank of material partially folded over upon itself;

Fig. 3 is a plan view of a pad constructed pursuant to our invention, the stitching not illustrated as completed in order to save drafting and a completed pad connected thereto being broken away to condense the drawing;

Fig. 4 is a section on the line 4—4 of Fig. 2;

Fig. 5 is a detail view schematically illustrating the overlocking stitch used;

Fig. 6 is a plan view of part of a sewing machine used in the practice of our invention;

Fig. 7 is a plan view of the work guide used;

Fig. 8 is a perspective view thereof;

Fig. 9 is an end view thereof.

Referring now to Figs. 1 to 5, a pad pursuant to our invention is formed from the blank 10 (Fig. 1) which is a single ply of suitable material preferably buckram or coarsely woven stiffened cloth. The blank 10 is in the form of an ellipse and is folded over upon itself (see Figs. 2 and 3) along the median line 12 extending from one comparatively pointed end 14 to the other comparatively pointed end 16.

There is thus formed the body of the pad 18 (Fig. 3) comprising the superposed layers of cloth 20 and 22 (Fig. 2) and the closed substantially straight rear edge 24 (Fig. 3) formed along the median line.

The open edges 26 and 28 (Figs. 2 and 3) of the superposed layers 20 and 22 are then sewed together in a conventional sewing machine, which has been modified as we shall describe, to form a trimmed edge 30 by the overlocking stitch.

This overlocking stitch is formed from three threads by three needles, which are conventionally operated and therefore need not be illustrated or described. The cams operating the needles are cut so that the stitches are close so that a comparatively continuous binding is formed by the threads.

Referring now particularly to Fig. 5, the first

thread 32 is sewed on top of the upper layer 22 and is provided with the lower sinker loops 34 inwardly of the open edges 26 and 28 and the upper sinker loops 36, just outside of the edges 28 and 26.

On the underside of the pad 18 on top of the lower layer 20, a second thread 38 is similarly sewed and is provided with the lower sinker loops 40 arranged inwardly of the open edges 26 and 28 and the upper sinker loops 42, just outside of the edges 28 and 26, which latter (42) are interlooped with the sinker loops 36 to constitute the edge of the binding of the pad.

A third thread 44, at the bottom of the overlocking stitch, gathers and interloops the lower sinker loops 34 and 40 of the first two threads 32 and 38 and sews the two layers 20 and 22 together.

It will now be recognized that by this construction, it is no longer necessary to provide a trim formed from a suitable ribbon at the rear edge 24 of the pad 18, the closed edge formed by folding the blank constituting a uniform substantially straight edge that cannot become separated, thereby not only reducing the cost of materials but forming an edge that will not become frayed or uncomfortable in wear.

It will further be recognized that a ribbon trim for the curved edge of the pad is also eliminated by the overlocking stitch which is comparatively less costly since it substitutes thread for a ribbon material. It will also be recognized that because of the interlooped threads of an overlocking stitch, the trimmed edge formed thereby will not become unraveled as may happen with the ribbon trimmed edge of prior art pads.

In operation folded over blanks are fed into the sewing machine, in the manner which we shall describe, so that the open edges are sewed together to form a continuous overlocking stitch along the trimmed edges 30 of the pads, which are thereby held together as a string, as illustrated in Fig. 3.

The pads are then separated by cutting the separating portions 46 of the overlocking stitch holding the separate pads together (Fig. 3), an operation which can not adversely affect the binding as was the case with prior art pads and the methods of manufacture heretofore available.

Referring now to Figs. 6 to 9, the folded over blank 48 as positioned on the work table or support 50 is fed to the conventional needles (not shown) by means of usual work feeding means 52.

In order to properly present the unsewed edges of the folded over blank 48 to the conventional cutting means (not shown) so that the edges may be suitably uniformly trimmed before they are sewed together with the overlocking stitches 30, we secure the work guide 54 to the work table, bent to conform to the shape thereof, by means of the set screw 55 passing through the slot 56 in the side 58.

The finger 60 extends upwardly from the element 62 above the table in advance of the needles and the cutting means to guide the blank thereto as the unsewed edges are held thereagainst in feeding the work to the needles. In this manner the resulting stitch also uniformly binds and shapes the edges of the pad to trim it.

It will now be recognized that not only does our invention provide a pad, in the nature of a hidden epaulet that is relatively inexpensive to produce by reason of the elimination of material in its manufacture, but in addition requires only 75

the use of comparatively unskilled labor and yet a pad that is extremely neat in appearance and rugged in wear.

We claim:

1. A string of pads, each pad in the nature of an epaulet, the pads of the string connected together by a line of stitching forming the trimmed edge of the pad, each pad connected to the adjacent pad by a portion of the stitching, a separate unattached pad being formed upon cutting away the said portion of the stitching connecting the pad to an adjacent pad, each pad formed from an elliptical in plan view blank of material folded over upon itself to form a substantially straight closed rear edge, a curvilinear front edge and a pair of superposed similar, equal in area elements in surface contact with each other, the line of stitching connecting the pads together formed by an overlocking stitch closing the curvilinear front edges of the folded over parts of material and sewing the said curvilinear edges together, said overlocking stitch formed from three threads, a first mentioned thread thereof sewed to the pad on the upper side thereof and having lower sinker loops inwardly of the curvilinear edge and upper sinker loops outside the curvilinear edge, a second thread thereof sewed to the pad on the underside thereof and having lower sinker loops inwardly of the curvilinear edge and upper sinker loops on the outside of the curvilinear edge, said upper sinker loops of the first and second threads being interlooped to form the binding edge of the pad, and a third thread thereof gathering and interlooping the lower sinker loops of the first and second threads.

2. The string of pads of claim 1, the curvilinear front edges and the substantially straight rear edge arranged across the weave of the material.

3. The method of forming a string of pads, each pad in the nature of an epaulet, which comprises forming a plurality of blanks, elliptical in plan view, each from a single ply of material, folding each blank upon itself to form the body of the pad of two superposed layers in contact with each other throughout the surfaces thereof and having a closed substantially rear edge and an open edge formed by the aligned curvilinear edges of the blank and sewing the open edges of each blank by means of a continuous overlocking stitch which forms a trimmed edge of each pad and a connecting portion joining the pads together, said overlocking stitch formed by three threads, the first of said threads on one side of the blanks, the second of said threads on the other side of the blanks, said first and second threads being interlooped on the outside of said open edge, and the third of said three threads gathering and interlooping the first and second threads inwardly of the open edge.
